HOUSING FOR A MAGNETIC CARD READER

Richard Hollerith, Jr., Upper Montclair, Franklin M. Raddin, Morristown, and William G. Benson, West Orange, N.J., assignors to Monroe International Corporation, a corporation of Delaware

Filed Mar. 31, 1964, Ser. No. 79,260

Term of patent 14 years

(Cl. D26—5)

FIG. 1

FIG. 2

FIG. 3

FIG. 4

FIG. 1 is a front perspective view of a housing for a magnetic card reader.

FIG. 2 is a left side elevational view thereof;

FIG. 3 is a rear perspective view of the housing.

FIG. 4 is a top plan view.

We claim:

The ornamental design for a housing for a magnetic card reader, as shown.
